UNITED STATES PATENT OFFICE.

ANAXIMANDER B. TUTTON, OF SIOUX FALLS, DAKOTA TERRITORY.

IRRIGATING ATTACHMENT FOR BOTTLES.

SPECIFICATION forming part of Letters Patent No. 330,755, dated November 17, 1885.

Application filed August 11, 1885. Serial No. 174,154. (No model.)

To all whom it may concern:

Be it known that I, ANAXIMANDER B. TUTTON, a citizen of the United States, residing at Sioux Falls, in the county of Minnehaha, Dakota Territory, have invented a new and useful Improvement in Irrigating Attachments to Prescription-Bottles, of which the following is a description.

Figure 1 is a view of the device when inverted for use, and Fig. 2 is a view of the device when not in use.

My invention relates to an improvement in irrigating attachments to prescription or other bottles for applying medicinal solutions or other liquids directly to mucous-canals of the human or animal body, and which also acts to close the bottle as a cork.

The object of my invention is to furnish a device which may be attached to ordinary bottles or vials of any size, and, when so attached to a bottle or vial containing fluid for injection, to furnish an irrigator for the purpose above named, and also a stopper to the bottle. This device, when not in use, is sheathed within the attached bottle or vial, and is thus protected from an accumulation of dirt or foreign matter, is protected from breakage, and furnishes the most compact form for carrying or packing, as the whole apparatus, including the bottle or vial, occupies only the space occupied by the bottle or vial.

In the drawings, A represents a thin elastic soft-rubber socket or cap, which is adapted to be distended over the neck of any vial or bottle. Through the top of this cap there pass two rubber tubes, B and C, of which B is the longer, and from one to three feet in length, while C is about the length of the vial. B is the tube through which the liquid passes out, and C is the tube that admits air. B has a nipple, a', on its inner end, and a nozzle, a, with cap a² at its outer end, and C has its inner end open, but has a stopper, b, at its outer end. Both these tubes fit through the soft-rubber cap, so as to be drawn out or forced back into the bottle without leakage.

To operate the device, the plug or stopper b is removed from tube C, and the cap or stopper a² is removed from tube B, and the latter is pulled out of the bottle to its full

length. Then lay the bottle on its side until tube B is emptied of air and filled with liquid from the bottle. Then insert the nozzle of tube B into mucous-canal to be operated upon, and hold it in position with one hand, 55 and with the other hand invert the bottle and raise it to the length of tube B, or to any height within that length, as may be necessary or desirable, whereupon the weight of the column of fluid in the bottle and in tube B will forcibly inject the fluid into the mucous-canal, the tube C operating to allow the entrance of air into the bottle, thus releasing the fluid.

After use the tube B is sheathed back into 65 the bottle through its opening in the bottle-cap. The cap a² is fitted over the nozzle a of tube B, and cap a² being button-shaped, it is buttoned into and closes the hole in the bottle-cap. Plug b is then fitted into the external opening of tube C, and the bottle is closed. This obviates the use of a cork to the bottle and does away with a separate instrument for syringe.

The use of an ordinary syringe for injecting 75 fluids contained in a prescription-vial is attended with much loss of the fluid and with much inconvenience, for as the ordinary syringe cannot be inserted beyond its point into a prescription-vial, then, in order to get 80 at the contents, the fluid must be decanted into a more open vessel, and from there taken up by the syringe; or, if the more open vessel is dispensed with, then the operator must tip the vial to bring the fluid into contact with 85 the syringe-point, and this latter cannot succeed when the contents of the bottle become lowered below the last half of the capacity of the bottle. With my device the last drop can be drained from the bottle, and the loss of the 90 fluid is reduced to the minimum.

Another advantage is that medicinal solutions intended to be used for injections are often nauseous, unwholesome, and poisonous if inadvertently taken into the stomach. 95 This inadvertence is prevented by the presence of my attachment on a bottle or vial.

Having thus described my invention, what I claim as new is—

1. An irrigating attachment for prescrip- 100

tion-bottles, consisting of a soft-rubber cap, A, adapted to be distended over the neck of the bottle, the long tube B, having a nozzle at its outer end with an inclosing-cap, and the short tube C, having a stopper in its end, both of said tubes being arranged in the cap A, and adapted to be forced into the bottle or pulled out from the same, as described.

2. An irrigating attachment for prescription-bottles, consisting of a stopper for the

bottle and a long and short tube, B and C, passing through the same, the short tube being provided with a closing-plug and the long tube with a nozzle and an inclosing-cap, as and for the purpose described.

ANAXIMANDER B. TUTTON.
